(57) **CLAIM**

I claim the ornamental design for the "dissected toroid/mobius puzzle," as shown and described.

DESCRIPTION

FIG. 1 is a front elevation view showing the assembled position of my new design for a dissected toroid/mobius puzzle, characterized by a toroid subdivided into two interlocking rings; and,

FIG. 2 is a perspective view showing the design with its ring sections in a splayed position, the mobius ring element being in the vertical position.
